[57] CLAIM

The ornamental design for a windshield mount for a radar detector, as shown and described.

DESCRIPTION

FIG. 1 is a perspective view of the front, top, and left side of a windshield mount for a radar detector showing my new design with the broken lines shown for illustrative purposes only and forming no part of the claimed design;

FIG. 2 is a left side elevational view, with the right side thereof being a mirror image;

FIG. 3 is a front elevational view thereof;

FIG. 4 is a rear elevational view thereof;

FIG. 5 is a top plan view thereof;

FIG. 6 is a bottom plan view thereof.

FIG. 1

FIG. 2

FIG. 3
